United States Patent

Des. 242,309
Patented Nov. 16, 1976

242,309

CHAIR

David Woods, Quakertown, Pa., assignor to Quaker
Chair Corporation, Quakertown, Pa.

Filed May 9, 1975, Ser. No. 575,945

Term of patent 14 years

Int. Cl. D6—01

U.S. Cl. D6—69

FIG. 1 is a perspective view of a chair embodying the present invention;

FIG. 2 is a front view of the chair of FIG. 1;

FIG. 3 is a side view of the chair of FIG. 1 as viewed from the left side;

FIG. 4 is a side view of the chair of FIG. 1 as viewed from the right side;

FIG. 5 is a rear view of the chair of FIG. 1; and

FIG. 6 is a top view of the chair of FIG. 1.

I claim:

The ornamental design for a chair, as shown.
